Primary Examiner — Christian P. McLean

(74) **Attorney, Agent, or Firm:** Dicke, Billig & Czaja, PLLC

(57) **CLAIM**

The ornamental design for a display screen or portion thereof with a graphical user interface, as shown and described.

DESCRIPTION

The FIGURE is a front view of a display screen or portion thereof with a graphical user interface showing our new design.

The outermost broken lines show a display screen or portion thereof and form no part of the claimed design. The remain-

(Continued)

ing broken lines show elements of the graphical user interface that form no part of the claimed design.
